UNITED STATES PATENT OFFICE

103,232

DESIGN FOR A PLATE OR SIMILAR ARTICLE

George J. Higginson, New York, N. Y., assignor to Johnson Bros. (Hanley) Ltd., New York, N. Y., a corporation of Great Britain

Application January 2, 1937, Serial No. 66,874

Term of patent 7 years

To all whom it may concern:

Be it known that I, George J. Higginson, a citizen of the United States and a resident of the Borough of Bronx, county of Bronx, city and State of New York, have invented a new, original, and ornamental Design for a Plate or Similar Article, of which the following is a specification, reference being had to the accompanying drawing forming part thereof.

The drawing is a plan view of a plate showing my new design.

I claim:

The ornamental design for a plate or similar article, as shown.

GEORGE J. HIGGINSON.
